Shaw & Clegg

ATTORNEY

UNITED STATES PATENT OFFICE.

LOUIS A. MOLTEN, OF HOBOKEN, NEW JERSEY.

CLOSURE FOR CONTAINERS.

Application filed April 7, 1920. Serial No. 371,914.

To all whom it may concern:

Be it known that I, LOUIS A. MOLTEN, a citizen of the United States, residing at Hoboken, New Jersey, in the county of Hudson and State of New Jersey, have invented certain new and useful Improvements in Closures for Containers, of which the following is a specification, reference being had therein to the accompanying drawing.

10 My invention relates to improvements in closures for containers and is illustrated in the accompanying drawings in its application to a grease cup for the lubrication of machinery, although of course it will be readily understood that the invention is adaptable for use upon preserve jars and various other forms of containers for which a hermetic closure may be desired.

Referring to said drawings, Fig. 1 illustrates in perspective, part being broken away, a suitable form of grease cup embodying an application of my invention. Fig. 2 is a cross-section of the cap or closure of the same.

25 3 indicates a grease cup, and 4 a plunger having a ball 5 which is resiliently seated in the base or outlet 6 by a spring 7 upon said plunger, said plunger being secured in the riding yoke 8 for feeding the grease in the usual well known manner. 9 indicates the outer cover which may be knurled or otherwise formed at the periphery as indicated at 10 for turning the same and 11-11' indicate indentations diametrically 30 opposite adapted to seat within the recesses 12-12' in the top of the cup as shown, for securing the cover.

35 13 indicates a suitable disc of resilient material such as steel which is adapted to rest upon the projections 11-11' and likewise another disc beneath the same 14 which may be of paper or other suitable material which also rests upon the projections 11-11' when the cover 9 is off the cup. 15 indi-

cates a depression in the top of the cover 45 9 which causes the discs 13-14 to buckle at the centre bending slightly downwardly into the container such as the cup 3 when resting upon the periphery or top edge of the same due to the pressure exerted by 50 said projection 15, thereby snugly sealing or closing the same when the cover 9 is turned so as to lock the projections 11-11' into the recesses 12-12'. From the foregoing it will be readily apparent that by a 55 slight twist of the hand, the cover may be readily applied or removed and a secured hermetical closing may be thus effected.

A cover thus applied securely retains its position upon the cup or container and is 60 not likely to be shifted by vibration or handling.

Of course it will be understood that various modifications may be made in the construction and arrangement of parts without 65 departing from the spirit of the invention as claimed.

I claim:

1. In a closure of the class described, an outer cover adapted to be turned down upon 70 the container, a resilient member between said cover and the periphery of said container, and a projection from said cover adapted to force said resilient member against said periphery when the cover is 75 applied.

2. In a closure of the class described, a flanged outer cover adapted to be turned down upon the open end of a container, a projection from the centre of said cover 80 and a flexible disc between the same and the periphery of said container whereby when said cover is applied, said disc bears upon the entire of said periphery.

In testimony whereof I hereunto affix my 85 signature.

LOUIS A. MOLTEN.
